Primary Examiner — Natasha Vujcic

(57) **CLAIM**

The ornamental design for a lamp, as shown and described.

DESCRIPTION

1.1 is a left perspective view, showing the design.

1.2 is a front view, showing the design.

1.3 is a top view, showing the design.

1.4 is a right perspective view, showing the design.

The broken lines in the drawings illustrate portions of the lamp and form no part of the claimed design.
